UNITED STATES PATENT OFFICE.

LEE PERKINS BIGGERS, OF PALMERSVILLE, TENNESSEE.

PADDLE-WHEEL.

No. 853,055.

Specification of Letters Patent.

Patented May 7, 1907.

Application filed February 5, 1906. Serial No. 299,548.

To all whom it may concern:

Be it known that I, LEE PERKINS BIGGERS, a citizen of the United States, residing at Palmersville, in the county of Weakley and 5 State of Tennessee, have invented a new and useful Paddle-Wheel, of which the following is a specification.

This invention relates particularly to paddle wheels for steamers or other self-propelled boats, and one of the principal objects 10 is to provide a feathering paddle wheel of a novel character, in which the action upon the water can be reversed without altering the direction of movement of the wheel, so that 15 the boat can be propelled either forwardly or backwardly without reversing the engines. Furthermore, the wheels may be made to give a lifting or lowering action upon the boat.

Another and important object is to provide 20 a wheel of the above character that will exert no material end thrust upon the shaft carrying it, and thus will eliminate friction and wear.

The preferred embodiment of the invention 25 is illustrated in the accompanying drawings, wherein:

Figure 1 is a side elevation of the wheel when the mechanism is arranged to propel the boat in one direction. Fig. 2 is a top plan 30 view of the same. Fig. 3 is a side elevation of the wheel, portions of the frame being broken away and showing the disposition of parts when the wheel is arranged to propel in the reverse direction. Fig. 4 is a horizontal 35 sectional view through the same. Fig. 5 is a vertical sectional view through the structure arranged as disclosed in Fig. 1. Fig. 6 is a detail perspective view showing a pair of the 40 paddle sections. Fig. 7 is a horizontal sectional view therethrough and illustrating the paddle sections as they enter the guides. Fig. 8 is a detail perspective view of one of 45 the guides. Fig. 9 is a plan view, showing a plurality of the wheels with common means for operating the various guides thereof.

Similar reference numerals designate corresponding parts in all the figures of the drawings.

In the embodiment illustrated, a fixed 50 frame 10 is employed having boxings 10^a, which may be of any suitable character and is mounted on the vessel to be propelled in any manner desired. Journalized in the boxings 10^a is a paddle shaft 11, on which is fixed 55 a wheel frame comprising a hub 12, that is shown as solid though the particular struc-

ture thereof is not important. Circular concentrically disposed sets of bands are arranged around the hub in spaced relation thereto and to each other, being carried by spokes 15, 60 that are fixed tangentially to the hub, as shown in Figs. 1 and 3. The wheel is furthermore laterally reinforced by crossed braces 16, which connect the hub and inner set 13 of bands, and other braces 17 directly 65 connect said bands. These various braces, spokes, and the like are preferably sharpened along their forward edges so as to offer as little resistance as possible in their passage through the water.

Carried by the above described wheel frame are paddles, each of which is composed of a pair of blades or sections 18, journaled upon the frame by shafts 19, the axes of which are disposed nearer one edge than the 70 other, said shafts having bearings at their outer ends in the rim bands 14 passing through the bands 13, and having their inner ends journaled in the hub 12. These paddle sections are comparatively thin and are reinforced by the embracing arms 20 of angularly disposed fingers 21, said fingers being located preferably at substantially right angles to the blade sections and projecting outwardly beyond the outer sides of the wheel 75 frame when the sections are in their feathering or inoperative positions, as illustrated in Fig. 6. Braces 21^a connecting the paddle sections and fingers, strengthen and reinforce the latter. Rollers 22^a are preferably journaled on the outer ends of the fingers. For the purpose of maintaining the blade sections in operative position transversely of the wheel frame, guides 22 are employed which are located on opposite sides of the wheel 80 frame. Each of these guides consists of a curved holding bar 23, arranged in line with and in the path of movement of the fingers 21, said bars having inclined ends 24, forming entrance throats. The curved bars are secured to radial spokes 25, carried by spaced hub collars 26, journaled on the boxes 10^a, as 85 shown in Fig. 5. The said guides 22 are freely movable, and one of their positions is defined by stationary stops 27, carried by 90 the frame and extending inwardly toward the wheel, said guides being engaged by the extended ends 28 of certain of the spokes 25 of the guides. The position of said guides when held by the stops 27 is illustrated in 95 Figs. 1 and 2, in which case, it will be observed, the paddles will be held in operative

100
105
110

position when they are passing beneath the shaft. Retaining blocks 28^a are carried by the stops 27 and are disposed just outside the extended ends 28 of the spokes. The said 5 guides can also be held in diametrically opposite positions, as illustrated in Figs. 3 and 4, in which case the extended ends 28 of said guides are held by and between movable stop arms 29, mounted on upright rock shafts 30, 10 journaled on the frame, these rock shafts having at their upper ends handle levers 31, which engage quadrant racks 32. The simultaneous movement of the guides is secured through the medium of any suitable 15 gearing, as for instance, sprocket wheels 33, secured to said guides and engaged by chains 34, passing around other sprocket wheels 35, carried by an operating shaft 36, said shaft having suitable handle cranks 37, for 20 turning the same.

The operation of the wheel may be briefly described as follows: Said wheel is preferably completely submerged, though in case it is not to be used for reversing, the submergence 25 is not necessary. When the boat is running in one direction, the guides are turned so that they are held as illustrated in Figs. 1 and 2, by the stationary stops 27. Thus, as the wheel frame rotates, the outstanding fingers 30 of the paddle sections will enter between the guides, as shown in Fig. 7, and the rollers 22^a operating against said guides will cause the paddle sections to turn into substantial alinement, so that they will act against the 35 water through which they pass, and consequently, cause the propulsion of the vessel. As the fingers leave the guides, the blades, being again free, will turn to their feathering positions and will remain in the same until 40 they have passed over the shaft and the fingers again enter between the guides. To reverse the movement of the vessel, it is only necessary to turn the operating shaft 36, thereby partially revolving the guides until 45 they can be engaged by the arms 29, as illustrated in Figs. 3 and 4. The paddle sections or blades will then feather as they pass beneath the shaft and will be locked in operative positions as they pass over the same. Consequently, their action will be reversed with 50 a corresponding movement on the part of the vessel. In actual practice, the operating shaft 36 and the stop-actuating levers 31 will be located upon the deck or some convenient 55 position upon the vessel. The bearing of the hubs 26 on the boxings 10^a is important as the lateral strain, due to the bearings of the fingers against the guides is not brought upon the shaft 11, and this lateral strain is further relieved by the blocks 28^a.

In case a plurality of wheels are to be employed, the structure shown in Fig. 9 may be advantageously used, each wheel, as a whole, being designated by the reference letter A, 65 and being similar in all respects to those al-

ready described, with the exception of the gearing for the guides, which guides are indicated at B. In this case, gear wheels 33^a are secured to the guides, and meshing with said gear wheels are other gear wheels 34^a, carried by shafts 35^a, extending along opposite sides of the wheels. These shafts are connected by gearing 36^a with a master shaft 37^a, by means of which said shafts can be turned, thus turning the guides. 70

It will thus be seen that a feathering and paddle wheel is provided of a comparatively simple nature and that the action thereof upon the water can be reversed without altering the direction of movement of the 80 wheel so that a boat can be propelled either forwardly or backwardly without reversing the engines. By altering the positions of the guides, the paddles may be made to have an elevating or lifting effect upon the boat or a 85 reverse lowering movement, thus making the structure useful in shallow water or in avoiding storms. Furthermore, by employing sectional paddles with oppositely disposed actuating means therefor, end thrusts upon 90 the shaft are avoided, thus eliminating friction and wear. In case the wheel is in backing position, or in any of the intermediate positions and it is desired to start the boat forward, it is only necessary to release the 95 guides and start the engine slowly, whereupon the guides will be automatically moved by the wheel until stopped in the desired relation. The frame 10 may be latticed to prevent logs, ice or other obstructions from 100 coming into contact with the wheel.

From the foregoing, it is thought that the construction, operation, and many advantages of the herein described invention will be apparent to those skilled in the art, without further description, and it will be understood that various changes in the size, shape, proportion, and minor details of construction may be resorted to without departing from the spirit or sacrificing any of the advantages of the invention. 105

Having thus described my invention what I claim as new and desire to secure by Letters Patent, is:

1. In a paddle wheel, the combination 115 with a rotatable support, of paddles mounted thereon, each paddle comprising sections separately journaled on the support and movable into substantial alinement transversely of the support, and separate devices 120 located exteriorly of and on opposite sides of the support for maintaining the paddle sections in such alinement.

2. In a paddle wheel, the combination 125 with a rotatable support, of paddles mounted thereon, each paddle comprising sections separately journaled on the support and movable into substantial alinement transversely of the support, separate normally stationary guides located exteriorly of and on 130

opposite sides of the support, and holding fingers carried by the paddle sections and disposed in angular relation thereto, said fingers engaging the guides and turning and holding the paddle sections in substantial alinement.

3. In a paddle wheel, the combination with a rotary support, of paddles comprising radially disposed sections separately journaled contiguous to their outer edges upon the support, outstanding fingers fixed to the pivoted edges of the paddles and disposed in angular relation to said paddles, and guides located on opposite sides of the support, the 10 paddles passing between the guides and the fingers engaging the same to turn and hold the paddle sections in transverse relation to the support.

4. In a paddle wheel, the combination with a rotary wheel having spaced rims, of paddle sections journaled in the rims and having angularly disposed fingers that are arranged to project outwardly beyond the outer sides of the wheels, and guides mounted 20 concentrically of the wheels on opposite sides thereof and extending but partially about the same, said fingers engaging the guides and thereby turning and holding the paddle sections in transverse relation to the 25 support.

5. In a paddle wheel, the combination with a rotary support, of feathering paddles journaled thereon, guiding means for holding the paddles against their feathering positions, means connected to the guiding means for moving the same, and means separate from the moving means and movable into and out of the path of movement of the guiding means for locking said means against 30 movement.

6. In a paddle wheel, the combination with a fixed frame, of a rotary support journaled thereon, feathering paddles journaled on the support, movable guiding means for holding the paddles out of their feathering positions, and means mounted on the frame and movable into and out of the path of movement of the guiding means for locking the latter against movement.

50 7. In a paddle wheel, the combination with a fixed frame, of a rotary wheel frame journaled thereon, feathering paddles mounted on the wheel frame, movable guiding means for maintaining the paddles in a predetermined relation on the wheel frame, a stationary stop carried by the fixed frame and located in the path of movement of the guiding means for holding said guiding means in one position, and another stop movable into and out of the path of movement of said guiding means to hold the same in a different position.

8. In a paddle wheel, the combination with a fixed frame, of a wheel frame journaled thereon, co-operating feathering paddle sections journaled on the wheel frame and having oppositely disposed fingers that project on opposite sides of the wheel frame, when said sections are in feathering position, and guides located on opposite sides of the 65 wheel frame and in the path of movement of the fingers to turn said paddle sections to and maintain them in their operative positions.

9. In a paddle wheel, the combination with a fixed frame, of a wheel frame journaled thereon, co-operating feathering paddle sections journaled on the wheel frame and having oppositely disposed fingers that project on opposite sides of the wheel frame 70 when said sections are in feathering position, guides located on opposite sides of the wheel frame and in the path of movement of the fingers to turn said paddle sections to and maintain them in their operative positions, 75 and means for simultaneously moving the guides.

10. In a paddle wheel, the combination with a fixed frame, of a shaft journaled thereon, a wheel frame fixed to the shaft and including a hub, concentric bands surrounding the hub and spaced therefrom and from each other, spokes connecting the bands and hub and disposed tangentially of the latter, paddle sections journaled between the bands 90 and having shafts that are journaled in the hub, angularly disposed fingers carried by the sections, guides journaled on the shaft on opposite sides of the wheel and arranged to be engaged by the fingers to turn the paddle 95 sections of the wheel frame, operating means for the guides including a shaft having a handle crank, stationary stops carried by the frame for holding the guides in a predetermined position and movable into and out of the path of movement of the guides, said other stops including rock shafts, and handle levers carried thereby.

11. The combination with a plurality of paddle wheels having feathering blades, of 110 guides located on opposite sides of each wheel and constituting means for holding the blades in predetermined relations with respect to the wheels, gear wheels carried by the guides, and gearing connected to said 115 wheels for simultaneously moving the same.

In testimony that I claim the foregoing as my own, I have hereto affixed my signature in the presence of two witnesses.
